UNITED STATES PATENT OFFICE

LOUIS JENSEN, OF CHICAGO, ILLINOIS, ASSIGNOR TO UNITED AUTOMATIC REGISTER CO., OF CHICAGO, ILLINOIS, A CORPORATION OF ILLINOIS

TYPEWRITING DUPLICATOR

Application filed February 10, 1928. Serial No. 253,379.

This invention relates to a typewriter having combined therewith means for enabling an original form-strip and any desired number of copies to be filled in, or typed.

5 The primary object of the invention is to equip a standard typewriter, such as a Remington typewriter, with means adapting the machine to type an original strip and any desired number of duplicate strips, proper provision being made for maintaining the strips in proper alignment and maintaining the forms on the strips in proper registration.

10 Preferably a typewriter equipped with the improvement is provided with means for automatically feeding a plurality of carbon ribbons which are interleaved between the paper strips and which serve to produce the copy impressions.

15 It may be stated that the improved machine is adapted to the purpose of filling out sales slips, order blanks, accounting blanks, etc., a standard typewriter being adapted to the purpose of feeding a plurality of continuous form-strips through the machine and 20 printing thereon the material which is to be filled into the forms. The machine is also equipped with suitable register mechanism for maintaining the forms in register and with suitable edge-joggers for keeping the strips in accurate underlying relation.

25 The invention is illustrated in its preferred embodiment in the accompanying drawings in which—

30 Fig. 1 is a side elevational view of a typewriter supported on a stand (shown brokenly) and equipped with means whereby form-strips may be fed through the machine and typed; Fig. 2, a broken vertical sectional view taken as indicated at line 2 of Fig. 1 and showing the tension device for the strip-roll; Fig. 3, a plan view of the machine; Fig. 4, a vertical transverse sectional view taken as indicated at line 4 of Fig. 3; Fig. 5, a fragmentary sectional view taken as indicated at line 5 of Fig. 3 and showing ribbon-feeding means employed; Fig. 6, a broken sectional view taken as indicated at line 6 of Fig. 5 and showing the position of a double pawl as it is set when the arm for 45 actuating the ribbon-feeding means is located

at one side of the machine as shown in Fig. 3; Fig. 6^a, a view similar to Fig. 6, but showing the position in which the pawl is set when the actuating arm is transferred to the opposite side of the machine so as to effect a reversal of the feed of the ribbons; Fig. 7, a broken plan view taken as indicated at line 7 of Fig. 5; Fig. 8, a broken longitudinal vertical section taken as indicated at line 8 of Fig. 3, this view showing the presser-rollers which coact with the platen-roll in operative position; Fig. 8^a, a view similar to Fig. 8 but showing a different position of the parts; Fig. 9, a broken elevational view on an enlarged scale taken as indicated at line 9 of Fig. 3; Fig. 9^a, a broken vertical sectional view taken as indicated at line 9^a of Fig. 9; Fig. 10, a broken plan sectional view taken as indicated at line 10 of Fig. 8; Fig. 11, a broken sectional view taken as indicated at line 11 of Fig. 10; Fig. 12, a broken longitudinal vertical sectional view taken as indicated at line 12 of Fig. 10; Fig. 13, a front elevational view of the inclined front rest-plate, or guide-plate, which is shown at the right upper portion of Fig. 8; Fig. 14, a broken rear view, partly in section, showing the usual means for controlling the movements of the typewriter carriage; Fig. 14^a, a sectional view taken as indicated at line 14^a of Fig. 14; Fig. 15, a broken transverse sectional view taken as indicated at line 15 of Fig. 1 and showing a portion of the mechanism for controlling the movements of the carriage; and Fig. 16, a view showing a portion of the escapement device which controls the movement of the carriage in the operation of typing a word, for example.

40 In the embodiment illustrated, A designates a stand; B, a typewriter mounted on the stand and equipped with a transversely movable carriage B' in which is mounted a platen-roll B²; C, a strip-guide mounted on the carriage B', said strip-guide having means for supporting the form-strips as they are drawn into the typewriting machine and being equipped above the platen-roll with a rearwardly and upwardly inclined guide-plate C' in front of which the printed portions of the strips pass upwardly from the

platens; D (Fig. 8), a presser device co-acting with the platen-roll B² in the intermittent feeding of the strips; E, a register device and strip-jogging means associated with the front plate C'; F (Figs. 1, 9 and 9^a), an actuating device adapted to the purpose of releasing the presser-device D and permitting the projection of the register-pins from the position shown in Fig. 8 to the position shown in Fig. 8^a; G (Figs. 1 and 5-7), means for supporting and automatically feeding ink ribbons, or carbon ribbons; H (Figs. 3 and 4), a guide-member mounted on the rear upper portion of the main frame of the typewriter and equipped with cam-studs H', either one of which studs may serve to engage the means for actuating the copy-ribbons; I, a strip-supporting frame mounted on the stand A and projecting rearwardly therefrom, the frame I being, in the illustration given, equipped with a strip-carrying roll I'; and J, form-strips adapted to be fed through the machine and typed.

The supporting-stand A may be of any suitable construction. In the illustration given, the stand is shown provided at its rear upper portion with a cross-bar 1 and at its upper central portion with a cross-bar 2, these members serving to support the frame I.

The typewriter B may be assumed to be of standard construction, except for attachments enabling the machine to be used conveniently and effectively for filling in the forms of the form-strips and tearing off the slips which have been printed, or filled in.

The typewriting machine illustrated is a standard large size Remington machine. The main frame of the machine B is designated 3. It is equipped with transverse guides, or tracks, 3^a which support rollers 4 (Figs. 1 and 5) which are engaged by transverse guide-rails 4^a with which the carriage B' is equipped.

The carriage is fed across the main frame in the usual manner as the typing operation proceeds. The type bars 5 (one shown in Fig. 3) are mounted on the main frame and actuated in the usual manner by means of the keys 5^a. The carriage is actuated by means of a clock-spring 6 (Fig. 14) which is housed in a drum and to a fixed shaft 6^b mounted on the main frame. The movement of the carriage is controlled by a rack 7 which is engaged by a pinion 7^a mounted on a shaft 7^b suitably journalled on the main frame. The drum 6^a is connected by means of a strap 8 with a goose-neck member 9 fixedly mounted on the typewriter carriage. The shaft 7^b is equipped with an escapement-wheel 10 which is controlled in the usual way to permit the feeding of the carriage as the typing proceeds.

The main frame of the typewriting machine is ordinarily equipped with a ribbon 11

(Figs. 3 and 8) which passes at the center of the machine back of a forked guide 12 at a point where the type makes the impression. In the illustration given, provision is made for feeding an original strip and three copy strips through the machine, and the mechanism G is equipped with three ribbons adapted to produce the copies, these three ribbons being designated 11^a.

The carriage B' of the typewriter is equipped with the usual devices for effecting the turning of the platen-roll, making various adjustments etc. Some of the features ordinarily present for these various purposes have been omitted from the drawings, for clearness of illustration. The platen-roll is shown equipped with a knob, or wheel, 13 by means of which the platen-roll may be turned to effect the feed of the strips. Other devices for controlling the angular position of the roll, etc. are omitted, for the sake of clearness.

The frame C (Figs. 1, 3, 8 and 13) preferably comprises a pair of sheet-metal bracket-members having standard portions 14 mounted on and rising from the rear rail 4^a of the carriage B', said bracket-members being equipped with rearwardly extending arms 14^a; the inclined front plate C' which is attached to forward extensions 14^b of the bracket-members; a front set of transverse guide-rods 15 disposed a short distance back of the platen-roll; and a rear set of transverse guide-rods 16, the guide-rods mentioned being supported at their ends by the bracket-members 14 and the rearward extensions 14^a thereof.

The strips of paper are supported on the guide-rods as will be clearly understood from Fig. 8. The guide-rods are equipped with adjustable edge-engaging members 17 which serve to center the strips properly in their passage through the frame C.

The presser-device D which co-acts with the platen-roll B² is of well known construction. It comprises small rolls 18 (Fig. 8) mounted in a cradle 18^a which is adapted to embrace the lower portion of the platen-roll. The device D comprises suitably related levers which carry the cradle 18^a and the rollers 18. One of these levers 19 is shown equipped with an arm 19^a adapted to be actuated through the medium of a shaft 20 and a cam-arm 20^a to withdraw the presser-device from the platen-roll, it being noted that a suitable spring, or springs, such as the spring 21 normally causes the presser-device to engage the strips of paper which pass about the platen-roll. The shaft 20 is equipped with an actuating arm 20^b which, as shown in Fig. 9, is adapted to be actuated by the device E.

It may be stated that the presser-device D really constitutes a part of the feeding mechanism. That is, the device D co-acts with

the platen-roll B² to effect feeding of the strips.

The register and edge-jogging mechanism E will be understood by reference to Figs. 8-13. It comprises a rock-shaft 22 equipped with spring-projected register-pins 22^a, an actuating arm 22^b, cam-arms 22^c, and a torsion-spring 22^d; a rock-shaft 23 equipped with a cam-arm 23^a and equipped also with bent arms 23^b adapted to hold the register-pins 22^a in retracted position, as shown in Fig. 8; and a pair of edge-jogging devices 24, each of said devices being secured at its upper end by a pivot-screw 25 to a slotted bracket-member 26 which is secured to the rear surface of the plate C'. Each of the members 24 has a cam-arm 24^a and a tappet-arm 24^b, each tappet-arm being provided with a rearward extension 24^c.

20 The register-pins 22^a are in the form of sleeves which have closed front ends of rounded formation. These sleeves are slidably mounted on pins 22^e which project forwardly and upwardly from the shaft 22. 25 The sleeves are provided with flanges 22^f. Between these flanges and the rock-shaft 22 are confined coil-springs 22^g.

The plungers 22^a are adapted to work through slots 27 in the front guide-plate, 30 or rest-plate, C'. The arms 23^b with which the rock-shaft 23 is provided are adapted to hold the register-pins 22^a in retracted position normally. The arm 23^a normally is held in the elevated position shown in Figs. 1 35 and 9 by a cam constituting a portion of the mechanism F. When the mechanism F is actuated to throw the presser-device D to the released position shown in Fig. 8^a, the arm 23^a is permitted to drop, thus allowing 40 the register-fingers 22^a to be projected through the slots 27 with the paper strips released from pressure and the register-fingers 22^a engaging register-perforations 28 with which the strips are provided, the lever 45 22^b may be actuated to oscillate the shaft 22, thus causing the register-fingers to swing upwardly and downwardly, as will be understood from Fig. 8^a. In this action, the cam-arms 22^c serve to swing the members 24 about 50 the pivots 25, and thus the tappet-arms 24^b are swung towards each other, thus tapping the opposite edges of the strips of paper and insuring proper longitudinal registration of the strips. At the same time, proper registration 55 of the forms on the strips is secured by the register-fingers 22^a.

The arm, or actuating lever, 22^b works through a slot 29 in the plate C'; and the forward extensions of the tappet-arms 24^b 60 work through slots 30 in the plate C'. The slots 30 are of sufficient length to permit adjustment of the joggers, or tappet-devices, 24.

As appears from Fig. 11, the devices 24 65 are equipped with springs 24^d which actuate the members in one direction, while the cam-

arms 22^c actuate them in the other direction.

As shown, the rock-shafts 22 and 23 are suitably journaled in the frame C.

The device F which serves to release the presser-device D from the platen-roll and to permit the register-fingers 22^a to be projected through the register-perforations 28 of the strips consists of a bell-crank 31 journaled in a bearing 32 with which the typewriter carriage B' is equipped, the bell-crank 31 having a long actuating arm 31^a and a shorter arm 31^b.

The arm 31^b is equipped with a pin 33 having pivotally connected therewith rearwardly extending links 34 and 35. The link 34 is in the nature of a thrust-bar which has a reduced extension at its rear end which extends through a perforation 34^a in the arm 20^b. The link 35 is connected at its rear end to a wrist-pin 36 carried by a crank-member 36^a journaled on a pivot-stud 37 which is secured to the bracket-member 14. The member 36^a is equipped with a cam 36^b which serves to actuate the arm 23^a as will be understood from Fig. 9. When the crank 31^a is thrown rearwardly from the position shown in Fig. 9, the member 20^b is actuated to release the presser-device D which cooperates with the platen-roll, and, at the same time, the flat-portion 36^c of the cam 36^b is brought into position to permit the arm 23^a to drop, thus permitting the register-fingers 22^a to be projected to the position shown in Fig. 8^a.

As shown in Figs. 8 and 13, the inclined front piece, or paper-rest, C' is equipped centrally at its upper edge with an upwardly and rearwardly curved finger 38.

Referring to Figs. 3, 10 and 13, 39 designates a tear-off bar, or strip-severing device. This bar is provided at one end with an open-ended slot 39^a and at the other end with a T-slot 39^b. These slots engage headed studs 40 with which the lower portion of the inclined front plate C' is equipped. The upper edge of the bar is bevelled to provide a tearing edge, as indicated at 39^c.

The bar 39, as appears from Fig. 8, is disposed a short distance above the plane of the carbon ribbons.

The mechanism G for supporting and feeding the copy ribbons 11^a will be understood by reference to Figs. 1, 3, 5-7. This device comprises a pair of horizontal plates 41 disposed at the front corner portions of the typewriter carriage and formed integrally with a crosspiece 41^a equipped with a forwardly projecting flange 41^b which overlies the front rail 4^a of the typewriter carriage; studs, or posts, 42 rising from and secured to the lower ends of the plates 41, said studs being threaded at their upper ends and having screwed thereon nuts 42^a which terminate at their upper ends in hollow-handled posts 42^b; drums or spools 43 journaled on the posts 42 just above

the plates 41 and resting on leather pads 43^a, the spools 43 having the ends of the ribbons 11^a wound thereon; removable tubular clutch-members 44 disposed above the spools and equipped at their lower ends with pins 44^a which engage perforations with which the upper walls of the spools are provided and equipped at their upper ends with clutch-fingers 44^b which are formed by slotting a flange with which the member 44 is provided; springs 45 interposed between the nuts 42^a and a shoulder 44^c at the lower end of the bore of the member 44; and an actuator, designated generally G', which is adapted to be applied to the clutch-device 44 at either side of the machine, said actuator comprising a tubular clutch-member 46 adapted to slip freely over the nut 42^b and engage the clutch-member 44, a pair of ratchet-disks 47 and 48 fitted on the reduced sleeve 46^a and secured, by means of screws 49, to the member 46; a bent lever 50 having its base end journalled on a bearing 51 with which the member 46 is provided, said lever being provided with a slot 50^a adapted to engage either one of the cam-studs H'; a housing-member 52 forming with the base-portion of the lever a housing for the pawls employed; a double acting pawl 53 pivotally mounted on the base-portion of the lever 50 through the medium of a screw 54, said pawl having an upper pawl-arm 53^a adapted to engage the upper ratchet-wheel 47, and having a lower pawl-arm 53^b adapted to engage the lower ratchet-wheel 48, and said pawl being further provided with an arm 53^c through the medium of which the pawl may be thrown to one position or to the other, depending upon which of the ratchet-wheels is to be engaged; and a spring 55 connecting the arm 53^c with the off-set or vertical portion 50^b of the lever 50.

The actuator G' may be shifted from the clutch-member 44 at one side of the machine to the clutch-member at the other side of the machine when it is desired to reverse the direction of movement of the ribbons 11^a.

The device H (Figs. 1, 3 and 4) is in the form of a stiff metal bar 56 which is supported on bracket-members 57 carried by the rear portion of the main frame of the typewriter, the end-portions of the bar being bent upwardly and inwardly towards each other, thus forming loops 56^a through which the arms 14^a of the paper-supporting frame C extend. The cam-studs H' are mounted on the inner end-portions of the arms at the upper sides of the loops. When the carriage of the machine is fed transversely, the arms 14^a are, of course, moved transversely.

The frame I which supports the source of supply for the form-strips J is shown as comprising U-shape bar 58 whose arms extend forwardly and rest upon the cross-bar 1 of the stand A, the front ends of the arms

being equipped with hooks 58^a which engage the cross-bar 2; and standard-bars 59 which are rigidly secured to the arms of the U-shape member 58 a short distance in front of the web 58.

The lower ends of the standard-bars 59 depend below the member 58 and are provided with slots 59^a in which is movably supported a shaft 60 of a short tension-roll 60^a. The upper extremities of the bars 59 are provided with slots 59^b in which are supported the ends of the shaft 61 of the drum I' upon which the form-strips are wound.

As shown in Fig. 2, the shaft 61 has an extension 61^a which is engaged by a friction-sleeve 62 provided with an adjusting screw 62^a. The arm 62^b of the friction-device is equipped with a stud 62^c which engages one edge of the standard 59. By means of the adjustable friction-device, the desired amount of friction may be placed on the shaft of the drum I'.

In practice, it is preferred to have the form-strips drop in loops from the paper-roll. The upper loop preferably is the shortest and is engaged by the gravity acting roll 60^a which serves to maintain the desired tension. The turning of the paper-roll to unwind the strips to the required degree is thus effected by the upper strip.

The operation of the machine may be described briefly. The strips may be threaded into the typewriter between the platen-roll B² and the co-acting presser-device, or feed-element, D, after the crank 31^a of the device F has been thrown upwardly and rearwardly, in which action the member 20^b serves to actuate the shaft 20 and release the device D from the platen-roll, as shown in Fig. 8. In this action, also, the cam-device 36^b is rotated, thus permitting the arm 23^a to fall and allowing the register-fingers 22^a to be projected to the position shown in Fig. 8^a.

The advance portions of the strips are interleaved with the carbon ribbons, and the perforations 28 at the advance ends of the strips are brought into engagement with the register-fingers 22^a. This is accomplished while the tear-off bar 39 is removed. The lever 22^b is then oscillated to bring the forms into registration, and in this operation the edge-jogging devices 24 are actuated to bring the strips into accurate longitudinal alignment.

The tear-off bar 39 is then applied and the machine is thereafter operated in the same manner as an ordinary typewriter. As the typewriter carriage travels transversely across the main frame, the device G serves to adjust the ribbons 11^a. The front ribbon 11 is adjusted in the usual manner.

As the typing proceeds, the strips are fed upwardly and rest on the inclined front plate C' and the curved finger 38. After a set of forms has been typed, the slips are torn from

70

the strips over the straight edge 39^c. The strips are then fed by means of the platen-roll until a fresh set of perforations at the front edges of the strips are in position to be engaged by the register-fingers 22^a; and, if necessary, the register-fingers are actuated to perfect the registration of the forms. From time to time, as may be necessary, the presser-device D is released and the perfecting of the 10 position of the forms with respect to each other is effected by means of the register and jogging mechanism.

The invention enables a standard typewriter to be used for typing or filling in 15 printed forms, very much as autographic registers are used, except that the forms are filled in by typing rather than by writing.

While the feature of the device for employing a plurality of ribbons is shown and 20 preferred, it is to be remarked that this feature may be omitted in case strips of carbon paper are interposed between the continuous form strips before the strips are wound into the roll shown in Fig. 1.

25 The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In combination with a typewriter carriage equipped with a platen-roll and means 35 co-acting therewith for feeding strips; a strip-supporting and guiding frame mounted on said carriage and equipped with a guide-plate rising from the front portion of the platen-roll, and registering and strip-aligning means mounted on said frame, said means including register-pins adapted to engage register-perforations in the advance portions of the strips and including also means for tapping the edges of the advance 40 portions of the strips.

2. In combination with a typewriter carriage equipped with a platen-roll and co-acting means for feeding strips; means for supporting and guiding the strips, including 50 a front guide-plate provided with apertures, register-pins disposed back of said guide-plate, means for projecting and retracting said register-pins through said apertures and means for vibrating the register-pins with 55 relation to the guide-plate while projected therethrough.

3. In combination with a typewriter carriage equipped with a platen-roll and co-acting feed-means; strip-supporting and 60 guiding means mounted on said carriage, including a front guide disposed above the front portion of the platen-roll, register-pins mounted back of said front guide and adapted to work therethrough, edge-tappets mounted back of said guide and adapted to work

therethrough, and a common actuating member adapted to oscillate said register-pins and edge-tappets.

4. In combination with a typewriter carriage equipped with a platen-roll and co-acting feed-means; a strip-supporting and guiding frame mounted on said carriage, said frame including standards and a front guide-plate mounted on said standards and rising from the front portion of the platen-roll, a 75 rock-shaft journaled in said standards and equipped with forwardly extending spring-projected register-pins adapted to work through perforations in said guide-plate, means for retracting said register-pins, edge-tappets working through said guide-plate, a lever connected with said rock-shaft and projecting in front of said guide-plate and adapted to actuate the rock-shaft, and means carried by said rock-shaft for actuating said 80 edge-tappets.

5. In combination with a typewriter carriage equipped with a platen-roll and co-acting feed-means; a strip-supporting and guiding-frame mounted on said carriage and 90 having standards equipped at their front portions with an upwardly and rearwardly inclined guide-plate, a rock-shaft mounted in said standards and equipped with forwardly extending spring-projected register-pins adapted to work through slots in said 95 guide-plate, edge-tappets mounted at the rear of said guide-plate and having portions working through slots in said guide-plate, a second rock-shaft mounted back of said 100 guide-plate and equipped with arms serving to retract said register-pins, means for oscillating said first-mentioned rock-shaft, and means for actuating said second-mentioned 105 rock-shaft.

6. In combination with a typewriter carriage equipped with a platen-roll and co-acting feed-means; a strip-supporting and guiding-frame mounted on said carriage, said frame including standards mounted on the carriage and a front guide-plate carried by 110 said standards, a rock-shaft equipped with a spring serving to actuate the rock-shaft in one direction and equipped with a forwardly extending lever adapted to actuate the rock-shaft in the other direction, spring-pressed plungers mounted on said rock-shaft and adapted to engage register-perforations when in the projected position, a second rock-shaft mounted in said frame above said 115 plungers and equipped with means for holding the plungers in retracted position, a crank mounted on the front portion of the typewriter carriage, and means actuated by said crank and serving to actuate said second-mentioned rock-shaft.

7. In combination with a typewriter carriage equipped with a platen-roll and with a co-acting retractable presser-device; a strip-supporting and guiding-frame mounted on 120

said carriage and provided with a front guide-plate extending upwardly from the front portion of the platen-roll, an oscillatable rock-shaft equipped with spring-projected register-pins adapted to work through openings in said guide-plate, a second rock-shaft equipped with means for retracting said register-pins, and an actuating device adapted to release said presser-device and said second-mentioned rock-shaft to permit operation of the register-pins while the strips are released from the platen-roll.

8. In combination with a typewriter carriage equipped with a platen-roll and a co-acting presser-device; strip supporting and guiding means mounted on said carriage; register-pins mounted on said carriage and normally held in retracted position with respect to the path of strips led over said strip supporting means, means mounted on said carriage serving to release said presser-device and project said register-pins into said path, and means for oscillating said pins while in projected position to effect proper registration of the strips while the strips are released from the platen-roll.

9. In combination with a typewriter carriage equipped with a platen-roll and a co-acting presser-device equipped with an upwardly extending actuating-arm; strip-supporting and guiding means mounted on said carriage, an oscillatable rock-shaft mounted on said carriage and equipped with spring-projected register-pins, a second rock-shaft equipped with means normally holding said register-pins retracted and equipped also with an actuating arm, a rotatable cam co-acting with said second-mentioned arm, a crank mounted on the front portion of the typewriter carriage, and links extending rearwardly from said crank and serving to simultaneously actuate said first-mentioned arm and said cam, whereby the paper-strips and the register-pins will be released by the movement of said crank.

10. In combination with a typewriter carriage equipped with a platen-roll and co-acting feed-means; strip-supporting and guiding means mounted on said carriage and including a front guide-plate rising from the front portion of the platen-roll, a spring-held rock-shaft equipped with spring-projected register-pins extending forwardly above the platen-roll and adapted to work through openings in said guide-plate, an actuating lever connected with said rock-shaft and extending in front of said guide-plate, means for normally holding said register-pins retracted, and a tear-off bar removably mounted on said guide-plate below the plane of said register-pins.

11. In combination with a typewriter having a movable carriage, a pair of ribbon-supporting spools mounted on said carriage and equipped with clutch-members, a pair of cam-

studs supported on the main frame at opposite sides of the machine, and an interchangeable device equipped with a clutch-member adapted to engage either one of said first-mentioned clutch-members and equipped with an actuating arm adapted to engage either one of said cam-studs.

12. In combination: a typewriter having its main frame equipped with a lever-actuating member, a carriage movably mounted on the main frame, ribbon-supporting means comprising a pair of spools having vertical axes mounted on said carriage, said spools being equipped with upwardly extending sleeves equipped with clutch-members, a clutch-member adapted to engage one of said first-mentioned clutch-members and equipped with a pair of ratchet-wheels, and an actuating lever pivotally mounted on said second-mentioned clutch-member and equipped with a double-acting pawl, said lever being adapted to engage said lever-actuating arm.

13. In combination: a typewriter, lever-actuating means mounted on the main frame of the typewriter, a pair of ribbon-supporting spools mounted on the carriage of the typewriter, and an interchangeable ratchet-device adapted to actuate either one of said spools and equipped with a lever adapted to be actuated by said lever-actuating member.

14. In combination with a typewriter carriage, a ribbon-supporting spool equipped with a clutch-member, and actuating means comprising a clutch-member equipped with a pair of ratchet-wheels, a lever pivotally mounted on said second-mentioned clutch-member and equipped with a double-acting pawl provided with an adjusting arm, and a housing mounted on said lever through which said arm extends.

15. In combination: a typewriter comprising a main frame having type and actuating keys mounted thereon and a transversely movable carriage equipped with a platen-roll and co-acting feed-means; strip-feeding and guiding means mounted on said carriage comprising a frame having rearwardly extending arms equipped with transverse guide-bars and having a front guide-plate rising from the front portion of the platen-roll, register and jogging mechanism associated with said front guide-plate, ribbon-supporting and feeding mechanism mounted on said carriage in front of said platen-roll and equipped with a rearwardly extending actuating arm, a loop supported on the rear portion of the main frame and equipped with a member adapted to actuate said last-mentioned arm in the movement of the carriage, the strip-supporting and guiding-frame being accommodated by said loop, and a strip-supply source mounted on a stationary support and from which strips may lead to the strip-supporting and guiding means mounted on said carriage.

16. In combination: a typewriting ma-

- chine having a carriage equipped with a plat-
en-roll and coacting feed means, a strip sup-
porting and guiding-frame mounted on said
carriage, means mounted on said frame for
5 tapping the edges of the strips, and mecha-
nism for actuating said edge tapping means.
17. In combination: a strip-supporting and
guiding frame; and mechanism mounted on
said frame for simultaneously tapping the
10 opposite edges of strips supported by said
frame to effect alignment of said strips.

LOUIS JENSEN.

CERTIFICATE OF CORRECTION.

Patent No. 1,882,635.

October 11, 1932.

LOUIS JENSEN.

It is hereby certified that the name of the assignee in the above numbered patent was erroneously described and specified as "United Automatic Register Co.", whereas said name should have been described and specified as "United Autographic Register Co.", as shown by the records of assignments in this office; and that the said Letters Patent should be read with this correction therein that the same may conform to the record of the case in the Patent Office.

Signed and sealed this 29th day of November, A. D. 1932.

**M. J. Moore,
Acting Commissioner of Patents.**
